ATTORNEYS

pivoted at 24 at a point intermediate said jaw and the upper end of said extension. A screw 25 threadedly extends through the jaw 19 above the clamping surface 20 thereof and into engagement with the upper end of the extension 22 of jaw 19. This screw may have a knurled head 26 at its end outwardly of jaw 19 for manually actuating the screw 25 for moving the clamping surface on jaw 23 toward the clamping surface 20 of jaw 19. The jaw 23 will swing by gravity away from the jaw surface 20 upon reverse rotation of the screw 25. 10

This clamping means on arm 18 is for securely gripping the flat closed end 27 of a conventional tube 28 of paint or paint pigment with the tube depending from said jaws.

At the side of bearing member 4 opposite to extension 15 5 are spaced opposed ears 29 and similar spaced opposed ears 30 are formed on sleeve 17 above the pair of ears 29.

An elongated handle or arm 31 extends at one of its ends between ears 30 for pivotal connection with said ears by means of pivot 32 and a link 33 similarly extends between ears 29 and is pivotally connected at one end thereto by pivot 34. The opposite end of link 33 is pivotally connected at 35 to the arm 31 at a point intermediate the ends of said arm.

The sleeve 17 is connected with post 3 against rotation by any suitable means. One such means may be a pin 36 that extends through the post 3 and into a laterally offset upper end 37 of a vertically extending slot 38 that may be formed in one or opposite sides of said sleeve (Fig. 2).

Upon elevating sleeve 17 slightly and giving it a fractional turn the ends of pins 36 will be at the upper end of slot 38 and the sleeve can then be moved upwardly until the ends of the pin are at the lower end of slot 38. The lower end of slot 38 is offset laterally at 40, with a slight downwardly opening recess in the upper side of the offset so that slight rotation of the sleeve will cause the ends of pin 36 to enter the offset 40, and the sleeve will then drop slightly by gravity so the ends of the pin will be in the downwardly opening recess in the upper side of the offset 40. This adjustment is to enable elevating the clamping means on arm 18 to either accommodate longer tubes or to enable a larger can 2 to be placed below the clamping means, or both. The bearing member 4 will follow the sleeve 17 since a spring 41 connects arm 31 with the upper end of the sleeve 17 for yieldably holding the member 4 against said sleeve and to return the member 4 after a downward movement of arm 31.

Adjustably secured on post 3 below the member 4 may be a collar 42. A thumb screw 43 may extend through the collar for securing the collar to said post in adjusted position vertically on said post. This collar limits the downward movement of the member 4, and consequently the downward movement of the rollers 6, 7. Post 3 may be graduated at 44 to provide visual means for setting the collar for different conditions, if so desired.

In operation, the operator may first remove the cover from the can 2 of the paint mixture, which can is positioned on base 1.

The desired tube of pigment is then selected and its closed end is secured between the jaws of the clamping member 5, the roller 7 being first swung away from roller 6 so the tube will depend past roller 6.

The roller 7 is then swung back and locked to roller 6 by the latch 13. When in this position the rollers 6, 7 are close to the clamping jaws 19, 23 so no objectionable pressure will be placed on the paint merely by locking the rollers together, and the rollers are relatively small in diameter so they will engage the tube very close to the clamping jaws of the tube gripping means.

The closure at the lower end of the tube that depends

from the clamping means and from the rollers is then cut off so the lower end of the tube will be fully open.

Collar 42 has previously been locked in position to limit the downward travel of the rollers to the lower end of the tube, but not past said lower end, so that no paint pigment will be deposited on the rollers.

The handle or arm 31 is then swung downwardly and the sides of the tube will be progressively forced flat together as the pigment is ejected from the tube directly into the can 2. When the lower end of the stroke of the arm 31 is reached, all of the paint in the tube will have been squeezed from said tube and deposited in the can, and a release of arm 31 will result in the bearing member and rollers moving back to the upper end of their stroke. The latch 13 is swung open and roller 7 swung away from roller 6 and upon loosening screw 25 the clamping means on the tube is released and the empty tube removed.

The lower end of the bearing member 4 may, if desired, be provided with collars 45, 46 (Fig. 6) between which the bearing member 47 at one end of a laterally projecting arm 48 is rotatably held. The outer end of said arm 48 has a presser plate 49 thereon. Plate 49 is greater in diameter than the can lid and has an annular flange 50 depending from its circular edge.

This presser plate may be swung from under the tube during a tube squeezing operation, but after the tube is emptied and removed from the device, the can lid 51 may be placed on can 2 and the presser plate 49 swung around to a position over the lid. Upon moving arm 31 downwardly, the presser plate will engage the lid and force it back to its seat in the top of the can. Any paint that might have entered the annular channel in the upper end of the can will be prevented from spouting onto the operator by the flange 50. Thus the can lid can be removed, the paint pigment squeezed into the can and the lid re-seated by the present device without touching the can.

In cramped quarters it has been found desirable in some instances to provide a tub squeezer in which the handle 31 projects to the side of the device at which the operator stands, and Fig. 5 shows such an arrangement, the handle being designated 52. This handle extends at an angle to the plane in which the post and rollers and tube gripping means are positioned. Thus the device can be placed near or even substantially against a wall that would otherwise interfere with the operation of handle 52.

It is to be understood that the detailed description is not to be considered as restrictive of the scope of the invention, but merely illustrative of one form thereof, for example, as seen in Fig. 7, a modified form of tube clamp may be used, in which the jaw 55, similar to jaw 19, is rigid with the upper arm 18 that is carried by a post. A movable jaw 56 is pivoted at its upper end to the outer end of arm 18 as at 57, and a projection 58 secured at one end to jaw 56 extends through the jaw 55 to project from the side of jaw 55 that is opposite to jaw 56. This projecting end 62 is pivotally secured at 63 to a cam clamp 59, which clamp has a handle 60 projecting upwardly therefrom when the low side of the cam engages jaw 55 and when the tube gripping lower ends of the jaw are open as seen in Fig. 7. A spring 61 interposed between jaws 55, 56 and around the projection 58 yieldably holds the jaw 56 open and the handle 60 in its upwardly extending position.

Upon moving handle 60 downwardly, the high side of cam 59 will draw jaw 56 to closed position and will compress spring 61 so that the closed end of a tube disposed between the lower ends of the jaws will be tightly gripped between said ends until the handle is swung upwardly, and when the handle is so swung, the jaw 56 will automatically open.

We claim:

1. A device for squeezing paint from a collapsible

walled tube that is closed at one end and open at its opposite end comprising: a horizontal base having a portion thereof adapted to support a can of paint thereon, a vertical post secured at its lower end to said base at one side of said portion, an arm secured at one end to said post at a point spaced substantially above said base and extending over said portion, tube gripping means carried by said arm at its outer end and over said portion, said tube gripping means including a pair of elements one movable relative to and toward the other for releasably gripping said closed end of such tube with the remainder of such tube depending freely therefrom, a member below said arm supported on said post for vertical reciprocal movement, said member including an extension projecting laterally from said post and positioned below said arm, a pair of horizontal opposed rollers carried by the outer end of said extension directly below said gripping means, roller mounting means supporting said rollers on said extension for movement of one relative to the other and toward each other into tight engaging relation to opposite sides of a tube adapted to be held at its closed end by said gripping means and at a point adjoining said closed end, means connected with said member for moving the latter, including said rollers, downwardly when said rollers are in said tight gripping relation to said tube whereby paint in such tube will be squeezed therefrom and into a container adapted to be positioned on said base.

2. A device for squeezing paint from a collapsible walled tube that is closed at one end and open at its opposite end comprising: a horizontal base having a portion thereof adapted to support a can of paint thereon, a vertical post secured at its lower end to said base at one side of said portion, an arm secured at one end to said post at a point spaced substantially above said base and extending over said portion, tube gripping means carried by said arm at its outer end and over said portion, said tube gripping means including a pair of elements one movable relative to and toward the other for releasably gripping said closed end of such tube with the remainder of such tube depending therefrom, a member below said arm supported on said post for vertical reciprocal movement, said member including an extension projecting laterally from said post and positioned below said arm, a pair of horizontal opposed rollers carried by the outer end of said extension directly below said gripping means, roller mounting means supporting said rollers on said extension for movement of one relative to the other and toward each other into tight engaging relation to opposite sides of a tube adapted to be held at its closed end by said gripping means and at a point adjoining said closed end, means connected with said member for moving the latter, including said rollers, downwardly when said rollers are in said tight gripping relation to said tube whereby paint in such tube will be squeezed therefrom and into a container adapted to be positioned on said base, and lid closing means carried by said member and movable to and from a position over said portion and over a can supported on the latter for downward movement therewith for urging a can lid on said can to closed position after paint from such tube has been discharged into the latter, said lid closing means being below said extension.

3. A device for squeezing paint from a collapsible walled tube that is closed at one end and open at its opposite end comprising: a horizontal base having a portion thereof adapted to support a can of paint thereon, a vertical post secured at its lower end to said base at one side of said portion, an arm secured at one end to said post at a point spaced substantially above said base and extending over said portion, tube gripping means carried by said arm at its outer end and over said portion, said tube gripping means including a pair of elements one movable relative to and toward the other for releasably gripping said closed end of such tube with the remainder of such tube depending therefrom, a member

below said arm supported on said post for vertical reciprocal movement, said member including an extension projecting laterally from said post and positioned below said arm, a pair of horizontal opposed rollers carried by the outer end of said extension directly below said gripping means, roller mounting means supporting said rollers on said extension for movement of one relative to the other and toward each other into tight engaging relation to opposite sides of a tube adapted to be held at its closed end by said gripping means and at a point adjoining said closed end, means connected with said member for moving the latter, including said rollers, downwardly when said rollers are in said tight gripping relation to said tube whereby paint in such tube will be squeezed therefrom and into a container adapted to be positioned on said base, means connected with said tube gripping elements for positively but releasably holding them in gripping relation with said closed end of said tube, and means connected with said rollers for positively but releasably holding them in position urging said opposite sides of said tube in engaging relation, said means for moving said member downwardly comprising an elongated handle pivotally connected at one end thereof to said one end of said arm and a link pivotally connected at one end thereof to said handle and pivotally connected at its opposite end to said member.

4. A device for squeezing paint from a collapsible walled tube crimped together at one end to form a flat sided closure and open at its opposite end comprising, a pair of tube gripping jaws connected for positive movement toward each other into engagement with opposite sides of said closure and means connected with said jaws supporting them spaced above a supporting surface for positioning a can below said tube with the latter depending from said jaws, a pair of rollers, roller mounting means supporting said rollers below said jaws and closely adjacent thereto for movement into tight engagement with said closure, means supporting said roller mounting means for downward movement away from said jaws when said rollers are in said engagement with said tube for squeezing the sides of said tube together to eject the contents thereof from its lower end, and stop means engageable with said roller mounting means during its downward movement for limiting the latter, said stop means being movable to different levels for varying the degree of downward movement of said roller mounting means and means for locking said stop means stationary in its different adjusted positions, and means connected with said roller mounting means for causing said downward movement thereof.

5. A device for squeezing paint from a collapsible walled tube crimped together at one end to form a flat sided closure and open at its opposite end comprising, a pair of tube gripping jaws connected for positive movement toward each other into engagement with opposite sides of said closure and means connected with said jaws supporting them spaced above a supporting surface for positioning a can below said tube with the latter depending from said jaws, a pair of rollers, roller mounting means supporting said rollers below said jaws and closely adjacent thereto for movement into tight engagement with said closure, means supporting said roller mounting means for downward movement away from said jaws when said rollers are in said engagement with said tube for squeezing the sides of said tube together to eject the contents thereof from its lower end, and stop means engageable with said roller mounting means during its downward movement for limiting the latter, said stop means being movable to different levels for varying the degree of downward movement of said roller mounting means and means for locking said stop means stationary in its different adjusted positions, and means connected with said roller mounting means for causing said downward movement thereof, said means for causing said downward movement thereof including a manually actuatable handle swingable downwardly for causing said movement,

and the means supporting said roller mounting means being a vertical post on which said last mentioned means is reciprocable, said means for supporting said gripping jaws above said surface being said posts.

6. A device for squeezing paint from a collapsible walled tube that is closed at one end and that terminates in a free lower edge at its opposite end comprising; a post and a base carrying said post upright thereon, a pair of horizontally opposed clamping jaws carried by said post in a position spaced from one side thereof for clamping the closed end of such tube with the remainder of said tube depending from said jaws, a pair of horizontally spaced, opposed rollers carried by said post in positions respectively adjacent to each of said jaws, means supporting said jaws on said post for movement toward each other into such clamping engagement with the opposite sides of said closed end and means supporting said rollers for movement toward each other into tube squeezing relation with such tube adjacent to its closed end when said closed end is clamped between said jaws, a lever one end of which is swingable about a stationary horizontal axis adjacent to said post and a horizontal

5 pivot carried by said post for so swinging said lever, means connecting said pair of rollers with said lever for downward movement of said pair of rollers along such tube from said closed end to said open end in one downward stroke of said lever when such tube is held by said jaws at its closed end and when said rollers are in squeezing engagement with said tube at a point immediately below said jaws, yieldable means connected with said lever for yieldably supporting said lever in a position adjacent to said jaws, and the space below said jaws and rollers being wholly unobstructed for downward movement of said rollers to the said terminating lower end edges of such tube.
